DESIGN FOR A TAP KNOB

Clark C. Merritt, Red Bank, N. J.

Application May 29, 1945, Serial No. 119,786

Term of patent 14 years

(Cl. D2—3)

To all whom it may concern:

Be it known that Clark C. Merritt, a citizen of the United States, residing at Red Bank, in the county of Monmouth and State of New Jersey, has invented a new, original, and ornamental Design for a Tap Knob, of which the following is a specification, reference being had to the accompanying drawing, forming part thereof.

Fig. 1 is a front elevational view of a tap knob showing my new design.

Fig. 2 is a rear elevational view,
Fig. 3 is a side elevational view,
Fig. 4 is a top plan view thereof, and,
Fig. 5 is a perspective view looking toward the back of the knob.

I claim:

The ornamental design for a tap knob, as shown.

CLARK C. MERRITT.
